UNITED STATES PATENT OFFICE.

FREDRICH J. RODE, OF CHICAGO, ILLINOIS, ASSIGNOR TO MARQUETTE TOOL & MFG. COMPANY, OF CHICAGO, ILLINOIS, A CORPORATION OF ILLINOIS.

HYDRAULIC CUSHION FOR SHEET-METAL PRESSES.

Application filed April 21, 1927. Serial No. 185,490.

This invention relates to improvements in hydraulic cushions particularly adapted though not necessarily limited in its use for sheet metal presses in which the metal is shaped by means of co-operating dies, one of which dies is reciprocable toward and away from the other, the work being clamped or held by means of a blank or work holding element that co-operates with the reciprocable die member, the blank or work holding element being resisted in its movement in one direction by the said cushion, and one of the objects of the invention is to provide an improved hydraulic cushion of this character in which a predetermined quantity of liquid is used in the cushion, the cushion embodying cylinder and piston members, the liquid being circulated from beneath the piston under predetermined conditions to relieve the pressure and then return to the pressure side of the piston for restoring the blank or work holding element.

A further object is to provide in a cushion of this character improved means for returning the liquid to the pressure side of the piston at a predetermined time in the cycle of operation of the press, and improved means for varying at will the time at which the said liquid is thus returned.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

40 The figure is a view partly in side elevation, partly broken away and partly in section of a sheet metal press having an hydraulic cushion constructed in accordance with the principles of this invention applied thereto.

45 Referring more particularly to the drawing the numeral 10 designates generally the bed or bolster plate of a sheet metal press, 11 the uprights, 12 a reciprocating ram to which a die 13 is connected and which ram is connected by means of links 14 to a crank shaft 15, and which shaft is rotated in any suitable manner and from any suitable source of power, not shown.

55 Mounted upon the bed plate 10 is a die 16

with which a blank or work holding member 17 co-operates and encompasses. The member 17 is supported by means of suitable pins 18 passing loosely through the bed plate 10 and engaging and resting upon a 60 pad or pin plate 19.

The pins 18 are of such a length that the upper surface of the member 17 will be normally held substantially flush with the upper surface of the die 16 to support the 65 work 20.

All of the above referred to parts are of the ordinary and well known construction.

Supported below the bed plate 10 is a support 21 which is preferably arranged 70 within a pit 22 and mounted upon the support 21 is a cylinder 23 in which a piston 24 reciprocates. A piston rod 25 connected with the piston 24 passes through a suitable stuffing box 26 in the top of the cylinder 23, 75 and is secured by means of suitable fastening devices 27, to the pad or pin plate 19. A vent opening 28^a may be provided in the cylinder 23.

80 A cylinder 28 telescopes over the cylinder 23 and is preferably of an internal diameter considerably greater than the external diameter of the cylinder 23 and is open at its bottom as at 29. A piston 30 is secured to the cylinder 23 and co-operates with the 85 cylinder 28 so that the end of the cylinder 23 also operates as a part of the piston.

The piston rod 25 passes through a suitable stuffing box in the end of the cylinder 28 and a member 32 may be secured to the 90 open end of the cylinder 28 as a safety device to prevent the cylinder 28 from rising too far with respect to the cylinder 23.

The cylinder 23 is provided with an opening 33 to which a pipe 34 is connected and 95 which pipe also has communication with an opening 35 through the piston 30.

A valve 36 controls the opening 33 and this valve is held in its seat by means of a resilient element 37 in the form of a spring 100 which operates upon the valve and the stress of the spring 37 may be varied by means of a suitable adjusting device 38.

105 The valve 36 is unseated against the stress of the spring 37 by the pressure of the liquid being forced out of the cylinder 23 and at a time when the stress of the liquid upon the valve 36 overcomes the stress of the spring 37.

110 The liquid forced from the cylinder 23

when the valve 36 is unseated will flow through the pipe 34 to be discharged into the cylinder 28 above the piston 30 thereby causing the cylinder 28 to rise.

- 6 When the cylinder 28 is lowered, in a manner to be set forth, the liquid will flow from between the piston 30 and the end of the cylinder 28 through an opening 39 into a pipe 40 and back into the cylinder 23 through an opening 41. A valve 42 is provided in the pipe 40 which operates to permit the liquid to flow from the cylinder 28 back into the cylinder 23, but will close to prevent the liquid from flowing from the cylinder 23 into the cylinder 28.

10 The initial supply of liquid may be supplied through a suitable inlet opening 43 controlled by a suitable valve (not shown). Thus it will be seen that when the piston 24 is lowered during the formation or shaping of the work the liquid in the cylinder 23 can find its way from the cylinder only through the passage 23, and as the valve 36 is set to operate at only a predetermined pressure, 15 the liquid in the cylinder 23 will act to resist the movement of the piston 24 in one direction and until the pressure of the liquid in the cylinder 23 overcomes the stress of the spring 37 to open the valve 36. At this 20 time the liquid will flow through the pipe 34 to raise the cylinder 28 with respect to its stationary piston 30.

When the cylinder 28 is forced downwardly the liquid will be forced out of the 25 opening 39 through the pipe 40, past the valve 42 and through the opening 41 into the cylinder 23, to raise the piston 24 and thereby restore the pad or pin plate 19.

As a means for lowering the cylinder 28 30 to force the liquid therefrom a resilient element 44, preferably in the form of a spring, any number of which may be provided, is provided and is supported by means of a formation or shoulder 45 carried by the cylinder 28. A rod or link 46 passes through the spring 44 and is provided with a washer or shoulder 47 which operates against the other end of the spring 44.

This rod or link is pivotally connected as 35 at 48 to one end of a lever 49 that is pivotally mounted intermediate its ends as at 50 to a fixed or stationary support 51.

Connected with the other end of the lever 40 is an antifriction roller 52.

55 As the cylinder 28 is raised the spring 44 and rod or link 46 will also be raised, causing the lever 49 to rock about its pivot 50 to lower the end of the lever carrying the antifriction roller from the position shown in 60 the figure. This operation will prevent the creating of any energy in the resilient elements 44.

In order to restore the cylinder 28 it is necessary to store or create energy in the 65 springs 44 by compressing the same and this

is accomplished preferably by means of a cam 53 which is adjustably secured by means of suitable fastening devices 54 to a rod or bar 55.

This bar 55 is connected to any suitable 70 movable portion of the press, here shown as the ram 12, and in the present form of the invention passes loosely through the bed plate 10.

Assuming the parts to be in the position 75 shown in the figure, the operation is as follows.

When the ram 12 descends the cam 53 will descend, causing the high portion of the cam 53 to pass out of engagement with the 80 anti-friction roller 52 and thereby position the low portion of the cam adjacent the roller 52. This will occur just at the time when the die 18 contacts with the work 20.

A further lowering movement of the ram 85 12 in the same direction will cause the pin plate 19 to be depressed through the medium of the member 17 and pins 18, thereby forcing the piston 24 downwardly in the cylinder 23. When a predetermined pressure 90 has been obtained on the liquid in the cylinder 23 the valve 36 will be opened and the piston 28 will be elevated in the manner described.

At this point in the operation and as the 95 low portion of the cam 53 is adjacent the roller 52 or end of the lever 49, the lever will rock about its pivot and no stress will be created in the spring 44.

When, however, the ram 12 starts to ascend 100 from this position, the high part of the cam 53 will contact with the roller 52 and thereby rock the lever 49 in the opposite direction about its pivot, thereby compressing the springs 44, and the energy thus 105 stored in the springs will force the cylinder 28 downwardly, causing the liquid between the piston 30 and the end of the cylinder 28 to be forced through the opening 39, pipe 40 and opening 41 into the cylinder 23 on the 110 pressure side of the piston 24 to restore the piston 24 and the pin plate 19.

While the preferred form of the invention 115 has been herein shown and described, it is to be understood that various changes may be made in the details of construction and in the combination and arrangement of the several parts, within the scope of the claims, without departing from the spirit of this invention.

120 What is claimed as new is:—

1. In a sheet metal working press a pressure pad, an hydraulic cushion for resisting the movement of said pad in one direction and embodying cylinder and piston members one of which members operates upon the pad, an additional and movable cylinder, a stationary piston co-operating with the latter, a conduit for leading liquid from the pressure side of the first said piston be- 125

- between the said movable cylinder and stationary piston, variable resistance means for controlling said conduit, a second conduit for leading the liquid from between the stationary piston and movable cylinder back to the pressure side of the first said piston to restore the latter, means for controlling the last said conduit, a normally inactive resilient element carried by the movable cylinder, a lever mounted upon a fixed pivot and operable upon said resilient element, and means connected with a movable part of the press for operating the lever at a predetermined time in the cycle of operation of the 10 press to create energy in the said resilient element to restore the said movable cylinder.
2. In a sheet metal working press a pressure pad, an hydraulic cushion for resisting the movement of said pad in one direction and embodying cylinder and piston members 20 one of which members operates upon the pad, an additional and movable cylinder, a stationary piston co-operating with the latter, a conduit for leading liquid from the pressure side of the first said piston between the said movable cylinder and stationary piston, variable resistance means for controlling said conduit, a second conduit for leading the liquid from between the stationary piston and movable cylinder back to the pressure side of the first said piston to restore the latter, means for controlling the last said conduit, a normally inactive resilient element carried by the movable cylinder, a lever mounted upon a fixed pivot and operable upon said resilient element, means connected with a movable part of the press for operating the lever at a predetermined time in the cycle of operation of the 30 press to create energy in the said resilient element to restore the said movable cylinder, and means for controlling at will the time of operation of the last recited means.
3. In a sheet metal press a pressure pad, an hydraulic cushion for resisting the movement of the pad in one direction and embodying a stationary cylinder, a piston therefor, a movable cylinder telescoping over the first said cylinder, the latter forming a portion of a piston for the movable cylinder, a conduit for leading the liquid from the first cylinder into the second cylinder, variable resistance means for controlling the conduit, a second conduit for leading the liquid back to the first said cylinder to restore the piston in the latter, a resilient element carried by the movable cylinder, a lever pivoted to a fixed support, an operative connection between the lever and said resilient element for compressing the latter to restore the movable cylinder when the lever is rocked in one direction, and means connected with a movable part of the press for thus rocking the lever at a predetermined time in the cycle of operation of the press.
4. In a sheet metal press a pressure pad, an hydraulic cushion for resisting the movement of the pad in one direction and embodying a stationary cylinder, a piston therefor, a movable cylinder telescoping over the first said cylinder, the latter forming a portion of a piston for the movable cylinder, a conduit for leading the liquid from the first cylinder into the second cylinder, variable resistance means for controlling the conduit, a second conduit for leading the liquid back to the first said cylinder to restore the piston in the latter, a resilient element carried by the movable cylinder, a lever pivoted to a fixed support, one end of the lever operating upon the resilient element, and means connected with a movable part of the press and operable upon the lever to create energy in the resilient element at a predetermined time in the cycle of operation of the press to restore the said movable cylinder.
5. In a sheet metal press a pressure pad, an hydraulic cushion for resisting the movement of the pad in one direction and embodying a stationary cylinder, a piston therefor, a movable cylinder telescoping over the first said cylinder, the latter forming a portion of a piston for the movable cylinder, a conduit for leading the liquid from the first cylinder into the second cylinder, variable resistance means for controlling the conduit, a second conduit for leading the liquid back to the first said cylinder to restore the piston in the latter, a resilient element carried by the movable cylinder, a lever pivoted to a fixed support, an operative connection between the lever and said resilient element for compressing the latter to restore the movable cylinder when the lever is rocked in one direction, and means connected with a movable part of the press for thus rocking the lever at a predetermined time in the cycle of operation of the press.
6. In a sheet metal press a pressure pad, an hydraulic cushion for resisting the movement of the pad in one direction and embodying a stationary cylinder, a piston therefor, a movable cylinder telescoping over the first said cylinder, the latter forming a portion of a piston for the movable cylinder, a conduit for leading the liquid from the first cylinder into the second cylinder, variable resistance means for controlling the conduit, a second conduit for leading the liquid back to the first said cylinder to restore the piston in the latter, a resilient element carried by the movable cylinder, a lever pivoted to a fixed support, a link connected with the lever and passing through said element to compress the latter when the lever is moved in one direction to create energy to restore the movable cylinder, and means connected with a movable part of the press for thus rocking the lever.

the lever at a predetermined time in the cycle of operation of the press.

7. In a sheet metal press a pressure pad, an hydraulic cushion for resisting the movement of the pad in one direction and embodying a stationary cylinder, a piston therefor, a movable cylinder telescoping over the first said cylinder, the latter forming a portion of a piston for the movable cylinder, a conduit for leading the liquid from the first cylinder into the second cylinder, variable resistance means for controlling the conduit, a second conduit for leading the liquid back to the first said cylinder to restore the piston in the latter, a resilient element carried by the movable cylinder, a lever pivoted to a fixed support, an operative connection between the lever and said resilient element for compressing the latter to restore the movable cylinder when the lever is rocked in one direction, means connected with a movable part of the press for thus rocking the lever at a predetermined time in the cycle of operation of the press, and means for varying at will the said time of operation of the last said means upon the lever.

8. In a sheet metal press a pressure pad, an hydraulic cushion for resisting the movement of the pad in one direction and embodying a stationary cylinder, a piston therefor, a movable cylinder telescoping over the first said cylinder, the latter forming a portion of a piston for the movable cylinder, a conduit for leading the liquid from the first cylinder into the second cylinder, variable resistance means for controlling the conduit, a second conduit for leading the liquid back to the first said cylinder to restore the piston in the latter, a resilient element carried by the movable cylinder, a lever pivoted to a fixed support, an operative connection between the lever and said resilient element for compressing the latter to restore the movable cylinder when the lever is rocked in one direction, and a cam device connected with a movable part of the press for thus rocking the lever at a predetermined time in the cycle of operation of the press.

9. In a sheet metal press a pressure pad, an hydraulic cushion for resisting the movement of the pad in one direction and embodying a stationary cylinder, a piston therefor, a movable cylinder telescoping over the first said cylinder, the latter forming a portion of a piston for the movable cylinder, one end of the said movable cylinder being open, a conduit for leading the liquid from the first cylinder into the second cylinder, variable resistance means for controlling the conduit, a second conduit for leading the liquid back to the first said cylinder to restore the piston in the latter, a resilient element carried by the movable cylinder, a lever pivoted to a fixed support, one end of the

lever operating upon the resilient element, and means connected with a movable part of the press and operable upon the lever to create energy in the resilient element at a predetermined time in the cycle of operation 70 of the press to restore the said movable cylinder.

10. In a sheet metal working press a pressure pad, an hydraulic cushion for resisting the movement of the pad in one direction and embodying a stationary piston and a movable cylinder co-operating therewith, a resilient element movable with the cylinder and normally inactive with respect to the cylinder, means for forcing a liquid between 80 the cylinder and piston to move the former, a member operable upon the resilient element to create energy therein, a lever pivotally mounted upon a fixed support, one end of the lever operating upon said member, and means connected with a movable part of the press and operable upon the lever at a predetermined time in the cycle of operation of the press to render the said member active with respect to said resilient 90 element, whereby the cylinder will be moved in a direction to force the liquid from between the cylinder and piston.

11. In a sheet metal working press a pressure pad, an hydraulic cushion for resisting the movement of the pad in one direction and embodying a stationary piston and a movable cylinder co-operating therewith, a resilient element movable with the cylinder and normally inactive with respect to the cylinder, means for forcing a liquid between the cylinder and piston to move the former, a member operable upon the resilient element to create energy therein, a lever pivotally mounted upon a fixed support, one end of the lever operating upon said member, means connected with a movable part of the press and operable upon the lever at a predetermined time in the cycle of operation of the press to render the said member active with respect to said resilient element, whereby the cylinder will be moved in a direction to force the liquid from between the cylinder and piston, and means for varying at will the time in the operation of 115 the press at which the last said means will operate upon the said member.

12. In a sheet metal working press a pressure pad, an hydraulic cushion for resisting the movement of the pad in one direction and embodying a stationary piston and a movable cylinder co-operating therewith, a resilient element movable with the cylinder and normally inactive with respect to the cylinder, means for forcing a liquid between the cylinder and piston to move the former, a member operable upon the resilient element to create energy therein, a lever pivotally mounted upon a fixed support, one end of the lever operating upon said mem- 120 125 130

ber, and a cam device connected with a movable part of the press and adapted to engage and rock said lever at a predetermined time in the cycle of operation of the press 5 to create energy in the said resilient element to restore the cylinder and thereby force the liquid from between the cylinder and piston.

13. In a sheet metal working press a pressure pad, an hydraulic cushion for resisting 10 the movement of the pad in one direction, a resilient element carried with the piston and normally inactive with respect thereto, means for forcing liquid between the piston and cylinder to move the former, a member 15 passing through said element and co-operating with the resilient element support for compressing the element to store energy therein to restore the piston and thereby force liquid from between the piston and 20 cylinder, a lever pivotally mounted upon a fixed support, one end of the lever being connected with the said member, and means responsive in its movement to the operation of a movable part of the press for rocking 25 said lever at a predetermined time in the cycle of operation of the press to render the said member active.

14. In a sheet metal working press a pressure pad, an hydraulic cushion for resisting 30 the movement of the pad in one direction, a resilient element carried with the piston and normally inactive with respect thereto, means for forcing liquid between the piston and cylinder to move the former, a member 35 passing through said element and co-operating with the resilient element support for compressing the element to store energy 40 therein to restore the piston and thereby force liquid from between the piston and cylinder, a lever pivotally mounted upon a fixed support, one end of the lever being connected with the said member, means responsive in its movement to the operation of a movable part of the press for rocking 45 said lever at a predetermined time in the cycle of operation of the press to render the said member active, and means for varying at will the time in the operation of the press at which the last recited means will operate 50 upon the said lever.

In testimony whereof I have signed my name to this specification, on this 15th day of April, A. D. 1927.

FREDRICH J. RODE.
